UNITED STATES PATENT OFFICE

99,380

DESIGN FOR A COMBINED ASH RECEIVER AND MOUNTING PANEL

John Visser, Grand Rapids, Mich., assignor to
Grand Rapids Metalcraft Corporation, Grand
Rapids, Mich., a corporation of Michigan

Application August 28, 1935, Serial No. 58,333

Term of patent 14 years

To all whom it may concern:

Be it known that I, John Visser, a citizen of the United States, residing at Grand Rapids, in the county of Kent and State of Michigan, have invented a new, original, and ornamental Design for a Combined Ash Receiver and Mounting Panel, of which the following is a specification, reference being had to the accompanying drawing, forming part thereof.

Figure 1 is a front view of a combined ash receiver and mounting panel in closed position, showing my new design.

Figure 2 is a side view of Fig. 1.

Figure 3 is a top view of the combined ash receiver and mounting panel of Fig. 1, with the ash receiver tilted to open position.

I claim:

The ornamental design for a combined ash receiver and mounting panel, as shown.

In testimony whereof I affix my signature.

JOHN VISSER.
